GAME, SUCH AS QUOITS

Alexander Weinberg, New York, N. Y.

Application April 20, 1933. Serial No. 667,115

5 Claims. (Cl. 273—106)

An object of my invention is to provide a game of the nature of quoits which will have the known advantages of quoits and also other advantages or attractions. Another object is to provide a game with the advantages named which, while capable of use indoors as well as outdoors and on shipboard, will require the minimum of apparatus and apparatus inexpensive to make and of attractive simplicity and ease of handling, especially in regard to the quoit itself.

My invention consists in whatever is described by or is included within the terms or scope of the appended claims.

15 In the drawing:

Fig. 1 is a perspective view of game apparatus embodying my invention and illustrating the manner of playing the game;

Fig. 2 is a transverse section through a quoit embodying my invention.

Fig. 3 is a view of a horseshoe-form quoit embodying my invention.

Briefly described, my apparatus in what I consider now its most desirable embodiment, comprises a quoit of a size and form readily to be held by the hand, and a target at which the quoit is thrown or tossed, the quoit having a vacuum cup and the target having a sufficiently flat and smooth surface so that an airtight joint will be made with the peripheral edge or lip of the cup with the result that the quoit will adhere to such surface and remain in the position it alights or falls thereon.

Describing in detail what is shown in the drawing, the quoit 10, is preferably a thin disc, flat on its opposite sides with a vacuum cup 11, secured or attached to a flat side of the disc, preferably concentric, and conveniently both disc and cup may be made in one piece of rubber. The cup, of course, is concave-convex, and it has a thin rim or edge so that it will snugly lie against a flat, smooth surface.

The target is preferably in the form of a readily portable board 12, with a flat, smooth surface marked off as by concentric circles 13, into areas that, respectively, have score values marked thereon by suitable numerals, which may lie flat upon a floor or table or be suspended or hung upon a wall. For floor or deck use, it may be preferred to support the target surface at a slight angle or incline and for that purpose, the far edge of the board may be provided with a down-turned flange 14. Besides the concentric circular score areas, small independent score areas 15, may be marked on the board surface.

A quoit, of course, may fall on a division line between two score areas. To determine the score value, what is the upper surface of the quoit has an index or pointer 16, at its edge which by pointing to the score area, determines the score. This index or pointer is of considerable value in the game because it introduces the desirable chance element, so that while there is room for the exercise of skill in tossing the quoit, nevertheless the possibility of turning of the disc in flight makes uncertain the actual score value, even of a skillfully thrown quoit. Since the quoit by the action of the vacuum cap will stick on the point of the target on which it happens to fall and will not be likely to tumble about to a different position, the skill of the player will count in placing the quoit, but as has been explained, the score value of the pitch or toss may be affected by the chance turning of the quoit.

Of course, the target may be the surface of a floor or a table and not a separate piece of apparatus. And, of course, the contour or shape of the quoits and that of the target may be varied.

Any desired number of quoits may be provided for use with the same target.

Preferably the diameter of the vacuum cup is substantially less than the diameter of the quoit body, so that there is an overhang, or projection of the body beyond the cup which, from inertia, imparts a desired pressure to the vacuum cup against the target surface and of course, the rim of the body stands above such surface around the edge of the cup so that such rim may be readily grasped to free the vacuum grip for lifting of the quoit from the target surface.

As I have already indicated, the form or shape of the quoit body may be other than a disc. For example, it may have the horseshoe shape body 100, shown in Fig. 3, with the vacuum cup 110, attached thereto at substantially the center by slender arms 17.

Obviously, the index may be applied to the top of the vacuum cup in such cases where the form of the body may make it preferable to apply the index to the vacuum cup.

What I claim is:

1. A quoit-form device of flat disc form with a vacuum cup on a flat side.
2. A quoit-form device of flat disc form with a vacuum cup on a flat side, the vacuum cup being substantially smaller in diameter than the disc.
3. A missile of quoit form having a vacuum cup on one side thereof to cooperate with a surface to which the same may be thrown to prevent sliding of the missile.

4. A missile of quoit form having a vacuum cup on one side thereof to cooperate with a surface to which the same may be thrown, to prevent sliding of the missile, said missile having an index to cooperate with score value areas upon the surface to which the missile is thrown.
5. A missile to be thrown at a target having a missile-receiving surface marked in areas of

differing score values, having a body of a size and form for ready throwing to such surface, and having a vacuum cup on the surface-striking side of the body and having an index to point to the score value of the throw, said vacuum cup fixing the missile on the struck surface.

ALEXANDER WEINBERG.
